CLAIM

The ornamental design for a mug as shown and described.

DESCRIPTION

FIG. 1 is a top, rear perspective view of a mug showing our new design;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is a bottom, front perspective view thereof.

The pairs of jagged broken lines are shown broken away to disclose indeterminate length, and the portions of the design that may be visible between such jagged lines have been removed for clarity. Neither the jagged broken lines nor portions of the design not visible from any part of the claimed design. The broken lines depicting the remainder of the mug form no part of the claimed design.
